UNITED STATES PATENT OFFICE

148,081

DESIGN FOR A BOAT

George T. Mertes, Superior, Wis.

Application June 24, 1946, Serial No. 130,964

Term of patent 7 years

(Cl. D71—1)

To all whom it may concern:

Be it known that I, George T. Mertes, a citizen of the United States, residing at Superior, in the county of Douglas and State of Wisconsin, have invented a new, original and ornamental Design for a Boat, of which the following is a specification, reference being had to the accompanying drawing, forming part thereof.

In the drawing

Fig. 1 is a side elevational view of a boat showing my new design;

Fig. 2 is a top plan view of Fig. 1, and

Fig. 3 is a stern elevational view of Fig. 1.

I claim:

The ornamental design for a boat, as shown.
GEORGE T. MERTES.
